Int. Cl. D12—02

U.S. Cl. D12—23

FIG. 1 is an upper left rear perspective view of a golf cart, showing my new design;

FIG. 2 is a lower left front perspective view thereof;

FIG. 3 is a fragmentary median longitudinal sectional view, to an enlarged scale, showing the golf ball rack, tee box and opposite rows of club shaft clips located on a plate supported on top of the stanchions extending upwardly from wheel axles; and

FIG. 4 is a right side elevational view thereof, showing the golf cart in its folded position.

I claim:

The ornamental design for a golf cart, as shown.
